SHOE UPPER FLANGING MACHINE

Wilfrid Thomas Minett, Leicester, England, assignor to United Shoe Machinery Corporation, Flemington, N. J., a corporation of New Jersey

Application January 28, 1941, Serial No. 376,277
In Great Britain January 31, 1940

34 Claims. (Cl. 12—97)

This invention is concerned with improvements in machines for forming flanges on shoe uppers and has particular reference to machines for forming outwardly turned flanges around the heel ends of the shoe uppers and comprises upper clamping and flange forming devices. A known machine of this character is described in United States specification No. 1,880,737.

One of the various objects of the present invention is to provide novel work positioning means, in a machine having upper clamping and flange forming devices, which will be capable of positioning uppers of various sizes without changing any of the parts of said means.

Another of the various objects of the present invention is to provide novel power operated mechanism, in a machine having upper clamping and flange forming devices, for operating such devices.

A machine, illustrative of the invention, which is hereinafter described is provided with an upper gauging device for positioning an upper in the machine in relation to upper clamping and flange forming devices of the machine. The gauging device consists of two plates, pivoted to the machine frame, against which the edge of the portion of the upper which is to be turned outwardly to form the flange is positioned. The plates have each formed in them one half of a U-shaped opening through which opening the flanging device projects.

The edge of each part of the opening is held against the flanging device by a comparatively light spring so that the plates can swing outwardly as the flanging device forms the outwardly turned flange and the plates can accommodate themselves to flanging devices of different sizes which may be used in the machine. It is therefore unnecessary to change the plates when the flanging device is changed. Further, since the edges of the opening are held, by the spring, against the flanging device there is no opening between the plates and flanging device into which the margin of the upper might project when the upper is presented to the machine and its edge around the heel end portion is placed against the gauging plates.

The illustrative machine also includes novel and convenient means for clamping an upper against an inside former of the machine around which the portion of the upper which is to be flanged is placed, said means being arranged to clamp the upper against the inside former without danger of marking or otherwise damaging the upper at the heel end thereof.

The illustrative machine is arranged to be operated by power mechanism which includes a crank and a toggle device so arranged that as the toggle of the toggle device is straightened the upper is clamped against the inside former and the crank causes, through the straightened toggle, the upper to be more firmly clamped and the flange to be formed on the upper.

In the accompanying drawings:

10 Figure 1 is a left hand side elevation of a head of the illustrative machine;

Figure 2 is a right hand sectional elevation of the head;

15 Figure 3 is a front elevation of the head viewed in the direction indicated by the arrow A in Figure 2;

Figure 4 is a section on the line IV—IV in Figure 3;

20 Figure 5 is a detail elevation, partly in section, of a clutch of the illustrative machine viewed in the direction of the arrow B in Figure 1;

Figure 6 is a section on the line VI—VI in Figure 5;

25 Figure 7 is a front elevation viewed in the direction of the arrow A in Figure 2 of a wiper of the illustrative machine;

Figure 8 is a section on the line VIII—VIII in Figure 7;

30 Figure 9 is a section on the line IX—IX in Figure 7; and

Figure 10 is a detail view of a brake device of the illustrative machine.

The said illustrative machine includes a machine head 1 which is supported on a column or base 3. The machine head 1 has formed in it at the front of the machine an upwardly and rearwardly extending guideway 5. The guideway is at an angle of forty-five degrees to the horizontal and has slidably mounted in it a cross-head 7. The cross-head 7 is in the form of a plate about eight inches wide and about seven inches long. The side edges of the cross-head have extending from them rectangular guides which engage in the guideway.

45 The machine head 1 has formed in it a second guideway 9, lying parallel to and mid-way of the guideway 5, in which is slidably mounted a slide member 11 which carries an inside former 13. The slide member 11 is about two inches wide.

50 The slide member 11 has projecting forwardly from it, about midway of its length, a headed pin 15 and at its upper end has extending upwardly from the front of it a horizontal flange 17 extending across the slide member. The inside former 13 extends upwardly above the slide mem-

ber 11 and at its lower end has formed in it an open-ended slot 19 into which the headed pin projects. The rear face of the inside former 13 engages the slide member 11 and has an overhanging lip 21 which provides an upwardly extending horizontal recess at the rear of the inside former. This recess engages the upwardly extending flange 17 on the slide member 11. By engaging the recess with the flange 17 and the open-ended slot 19 with the pin 15 the inside former 13 may be easily placed on the slide member 11 and by sliding the inside former upwardly to disengage the recess from the flange 17 and then moving it forwardly the inside former may readily be removed from the slide member 11 and a different former may be placed in the machine. The upper end of the inside former 13 is shaped to correspond to the heel end portion of an upper which is to be operated upon and has a plane rear face 23 lying parallel to the guideway 5 for the cross-head 7.

The headed pin 15 and flange 17 prevent the inside former 13 from moving forwardly and rearwardly and are arranged to allow the upper end of the inside former to rock slightly laterally. The slide member 11 has secured to its upper end, at the rear of the inside former 13 a cam plate 25 (Figure 2) the upper end of which is normally held against a stop face 27 on the machine head 1 by a compression spring 29 which engages at its upper end the upper end of a bore in the slide member 11 and at its lower end engages a washer 31 which is engaged by the upper end of an adjustable screw 33 in the machine head 1 below the slide member 11.

Pivots supported on the cross-head 7 are a pair of outside formers which press the heel end portion of the upper against the inside former 13. Each outside former comprises a block 35, 37 having an upper-engaging surface 39, 41 shaped to conform to about one half of the inside former 13 around its heel end and for some distance along the side of the inside former. The upper-engaging face 41 on the right hand block 37 extends further round the heel end of the inside former 13 than the upper-engaging face 39 on the other block 35 with the result that when the blocks are in engagement with the upper the joint between the two blocks at the heel end of the upper lies to one side of a vertical plane passing lengthwise centrally through the inside former 13. This arrangement prevents the extreme rear end of the upper, which may have on it a back strap, from being nipped or marked by the meeting edges of the faces 39, 41 on the blocks. The rear faces of the blocks and the rear face 23 of the inside former all lie on the same plane which is parallel to the guideway 5.

The blocks 35, 37 have projecting laterally from their outer side faces lugs 43, 43 which enter openings in block carriers 45, 47 and pins 49, 49 passing through bores in the block carriers and lugs secure blocks to their carrier. The pins 49, 49 have knurled heads formed on their forward ends by which the pins may be readily withdrawn and then the blocks 35, 37 may easily be removed from their carriers 45, 47 and a pair of blocks of a different size or shape may be secured to the block carriers, these blocks also having lugs projecting from them to enter the openings in the carriers and holes to receive the pins. The left-hand block carrier 45 has projecting towards the right from its upper end an arm 51 having a rounded end 53, the axis of which lies in the aforesaid vertical plane passing centrally

through the inside former 13, which engages a rounded recess formed in the upper end of the right-hand block carrier 47. The rounded end 53 of the arm 51 and the recess are held in an

53 of the arm 51 and the recess are held in engagement with each other by a tension spring 55 which is connected to pins 57 extending from the upper ends of the carriers 45, 47. The pins 57 are secured in projections 59, 59 on the carriers which extend upwardly, parallel to the guideway 10 5 for the cross-head 7, and enter a recess in the cross-head. The projections 59 and recess prevent upward or downward movement, at right angles to the guideway, of the upper ends of the block carriers 45, 47.

15 The upper end portions of the block carriers **45, 47** are connected to the cross-head **7** by a pair of links **61, 61** having rounded ends which seat in corresponding recesses in the block carriers and cross-head. Pins pass through the links **61** and are secured in the block carriers **45, 47** and cross-head **7**. The links **61** extend upwardly and outwardly from their pivotal connections to the block carriers at an angle of about thirty-five degrees to the aforesaid vertical plane.

25 The block carriers have extending rearwardly and downwardly from their upper end portions a pair of pins 63, 63 which enter open ended slots 65, 65 formed in the side margins of the lower end of an upwardly and rearwardly extending slide 67.

30 67. The pins 65, the pins in the lower ends of the links 61 and the rounded end 53 of the aforesaid arm 51 on the left hand block carrier 45 all lie, when the cross-head 7 is in its raised position, at about the same level heightwise of the machine.

35 The upper part of the slide 67 is guided in a guideway 69 formed in a bracket 71 secured on the upper part of the machine head 1. The slide 67 has formed in it a slot 73 which extends lengthwise of the slide and passing through the
40 slot and slidingly mounted in a bore in the bracket 71 is a headed pin 75, the head of which is pressed against the slide by a compression spring 77 between the machine head and a nut 79 threaded on the headed pin 75. Movement of the slide 67 in its guideway 69 is by this means
45 frictionally resisted.

The lower ends of the block carriers 45, 41 have pivoted to them by pins 81, 81 extending downwardly and rearwardly the upper ends of rods 83, 83 which from their upper ends extend downwardly and forwardly and also outwardly laterally of the machine. The rods 83 are slidably mounted in sleeve members 85, 85 which are pivoted at 87, 87 to the machine head 1. The sleeve members 85 each have in them a compression spring 89 which as the cross-head 1 is moved downwardly is engaged and compressed by the lower end of its rod 83. The cross-head 1 is normally held in a raised position in which the upper end of the cross-head 1 engages a face on the bracket 71 by a pair of compression springs 91, 91 one at each side of the cross-head, in bores extending lengthwise of the cross-head. The springs 91, 91 engage the ends of the bores and plungers 93, 93 in the lower ends of the bores which engage studs 95, 95 projecting from the machine head.

As the cross-head 7 is moved downwardly in its guideway 5 by a treadle operated mechanism hereinafter described, downward movement of the aforesaid slide 67 is frictionally prevented, and the links 61, 61 which are connected to the cross-head 7 and the block carriers 45, 47 cause the blocks 35, 37 to swing inwardly towards each other about the centre of the rounded end 53 of

the arm 51 on the left-hand block carrier 45 until their lower end portions engage the side of the heel end portion of an upper which has been placed on the inside former 13. During continued downward movement of the cross-head 7 the blocks 35, 37 wipe the upper down the sides of the inside former 13 and the slide 67 also moves down but owing to the friction exerted on the slide the blocks 35, 37 swing inwardly as they move down and press the upper against the sides of the inside former 13. As the crosshead 7 moves down the rods 83 which are pivoted to the lower ends of the block carriers 45, 47 move downwardly in and swing inwardly with their sleeve members 85 but the lower ends of the rods do not engage the upper ends of the springs 89 in the sleeve members until the blocks 35, 37 have been moved down so far that the upper portions of their inner curved surface are pressed against the upper. The upper which has been placed on the inside former 13 is in this manner wiped down and pressed against the inside former. As will hereinafter appear the blocks 35, 37 are pressed more firmly and the flange is formed on the upper, by flanging members, by power operated means.

The upper flanging members lie just behind the inside former 13 and comprise a pair of flanging blocks 97, 99 which are arranged to spread apart about a common axis 101 (Figure 7) to form the flange on the upper. When the flanging blocks 97, 99 are closed together the edge of the front face of the blocks conforms in size and shape substantially to the size and shape of the inside former 13. The left-hand block 97 (Figure 7) at its upper end has formed in it a cylindrically shaped recess 103 extending inwardly from its front face, the wall of which is concentric to the axis 101 about which the blocks move and the right hand block 99 has projecting from its upper end a lug 105 which is shaped to fit into the recess 103, the forward face of the lug being a continuation of the front face of the block. The outer edge of the right hand block extends, at the top of the block, to the left of the aforesaid vertical plane which passes centrally through the inside former 13. By this arrangement a continuous edge is provided around the front face of the flanging blocks which remains substantially unbroken as the flanging members are spread apart.

Each flanging member 97, 99 is detachably secured to the front of a flanging arm 107, 109 the front faces of which arms lie parallel to the aforesaid guideway 5 for the cross-head 7, by pins 111 secured in each arm and a hole in each flanging member and a forwardly and rearwardly extending face 113 on each flanging member and a face on a forwardly and upwardly extending flange 115 on each arm. The left hand arm 107 has extending downwardly and rearwardly from its upper end at right angles to the guideway 5 a sleeve 117 which is rotatably mounted in a sleeve bearing 118 (Figure 2) on the machine head. The right hand arm 109 has extending downwardly and rearwardly from its upper end a spindle 119 which is rotatably mounted in the aforesaid sleeve 117 on the left hand arm 107. The spindle 119 has secured on its rear end a washer 121 (Figure 2) which is larger in diameter than the sleeve 117 and prevents relative movement in one direction between the arms 107, 109. A face on the rear of the right hand arm 109 engages the forward end of the sleeve and prevents relative movement between the arms 107, 109 in 75

the other direction. The washer 121 normally engages a shoulder at the rear of the sleeve bearing 118 and is held against the shoulder by a compression spring 123 housed in a cylindrical chamber, coaxial with the axis of the sleeve and spindle, in the bearing 118. The rear end of the spring 123 is engaged by an adjustable screw 125, in the rear end of the chamber, by which the spring may be adjusted.

10 Each flanging arm 107, 109 has extending downwardly and rearwardly from it near its lower end a pin 127 on which is rotatably mounted a rectangular block 129. The blocks 129 engage in rectangular grooves 131 (Figure 3) in the 15 aforesaid cam plate 25 which is secured on the slide member 11 which carries the inside former 13. The rectangular grooves 131 extend upwardly and outwardly at an angle of ninety degrees to each other and the blocks 129 normally lie in 20 the lower ends of the grooves close to where the grooves meet.

The margin of the upper which is to be flanged outwardly, in the illustrative machine, is positioned rearwardly of the rear face of the inside former 13 by a pair of gauge plates 133 (Figures 2 and 3) the front faces of which are as far rearwardly of the rear face of the inside former 13 as the width of the margin of the upper which is to be turned outwardly. Each plate 133 is pivoted at 135 at its upper end to a head 137 on the forward end of a downwardly and rearwardly extending stem 139 which is slidably mounted in the machine head a little higher than the aforesaid sleeve 117 and spindle 119 on the flanging arms. The stem 139 extends downwardly and rearwardly at right angles to the cross-head guideway 5 and the pivots of the gauge plates are parallel to the stem and lie one at each side of the stem. The gauge plates 133 are urged about 30 their pivots, by a tension spring 141 connected at each end to the plates, towards the flanging members 97, 99. The lower portions of the gauge plates have in their inner edges recesses, the recess, which is U-shaped, formed between the 35 two plates extending around the top of and along the sides of the flanging members 97, 99. The inner edges of the recesses in the gauge plates engage the bottoms of recesses 143 (Figure 9) formed along the outer sides of the flanging members 97, 99. As the flanging members 97, 99 are spread apart to form the flange on the upper 40 the gauge plates 133 swing with them about their pivots 135 and if the flanging members are changed for others of a different size the plates 45 accommodate themselves to these members. Since the gauge plates are held by the spring 141 in engagement with the bottoms of the recesses 143 in the sides of the flanging members they are 50 always in a position to be engaged by the edge of the upper when the latter is presented to the 55 machine.

The aforesaid stem 139 which extends downwardly and rearwardly from the head 137 to which the gauge plates are pivoted has formed in 60 the left hand side of it a recess 145 into which projects an eccentric pin 147 projecting from the right hand end of a horizontal shaft 149 which is rotatably mounted in the machine head 1. The left hand end of the shaft 149 has secured on it 65 outside the head a hand lever 151 (Figure 1) by which the shaft may be rotated to adjust through the eccentric pin 147 the stem 139 and gauge plates forwardly or rearwardly. The hand lever has in it a spring plunger arranged to enter one 70 of a series of recesses 153 in the machine head

to hold the gauge plates in their adjusted position and these recesses indicate to the operator the distance of the front faces of the gauge plates from the rear face of the inside former and the width of the flange which will be turned outwardly.

The aforesaid cross-head 7 has secured in it studs 155 (Figure 4) which have secured in their rear ends pins 157 on which are pivoted the forward ends of a pair of parallel levers 159 which extend from the pivots rearwardly and downwardly. The studs 155 are secured in the cross-head near each side thereof. The rear ends of the parallel levers 159 are pivoted to the upper ends of a pair of radius arms 161 which are pivoted to the machine head 1 on horizontal coaxial pivots 163 extending laterally of the machine. As the crosshead rises and falls the front ends of the parallel levers 159 move in a straight path and the radius arms 161 swing forwardly and rearwardly. The parallel levers 159 have pivoted to them, by horizontal coaxial pivots 165 extending laterally of the machine, the forward ends of a pair of rearwardly extending parallel links 167, the pivots 165 being somewhat nearer the front ends of the levers than their rear ends. The rear ends of the parallel links 167 are pivotally connected, by a horizontal laterally extending shaft 169, to the rear ends of a pair of parallel eccentric links 171 which at their forward ends are pivoted on a pair of eccentrics 173 secured on a horizontal driving shaft 175 extending laterally of the machine and rotatably mounted in the machine head 1. The parallel and eccentric links 167, 171 form an inverted toggle which as will hereinafter appear in straightened by treadle operated means before the driving shaft 175 is caused to be operated.

A horizontal shaft 177 extending laterally of the machine is positioned a little rearward of the driving shaft 175 and is rotatably mounted in the machine head 1. The shaft 177 has secured on it a pair of upwardly projecting arms 179, the upper ends of which engage the rear sides of the eccentric links 171. Also secured on the latter shaft is a rearwardly extending arm 181 the rear end of which has secured in it a pin 183 which is arranged to be engaged by the upper end of a rod 185 connected to a treadle lever.

When the treadle lever is depressed the upwardly projecting arms 179 engage the rear sides of the eccentric links 171 and swing the links forwardly about the eccentrics 173, until the aforesaid shaft 169 at the upper ends of the eccentric links engages a stop face 187 on a block 189 which is secured on the machine head. As the eccentric links 171 are thus swung forwardly the toggle 167, 171 is straightened and the aforesaid parallel levers 159 are thereby swung downwardly about their pivotal connections to the aforesaid radius arms 161 and move the cross-head 7 downwardly to cause as hereinbefore described the outside formers to wipe down and clamp the upper against the inside former 13.

The block 189 has in it at the rear of the stop face 187 on the block a spring plunger 191. The spring plunger 191 can yield downwardly in the block 189 and its upper end is normally held in such a position that the aforesaid shaft 169 in the upper ends of the eccentric links can just pass over the upper end of the plunger. The distance between the stop face 187 on the block 189, which face controls the path of movement of the shaft

161 as the eccentrics rotate, and the front face of the plunger is only slightly greater than the diameter of the shaft 161. As the eccentric links 171 and cross-head 7 are lowered by rotation of the eccentrics 173 the shaft 161 moves down between these faces which prevent the shaft 161 from moving laterally during the rotation of the eccentrics and the toggle 167, 171 from being broken. Should the eccentrics 173 be caused to be rotated while the shaft 161 is above the plunger 191 the latter will yield downwardly and thus prevent damage to the machine.

When the illustrative machine is in its normal stopping position the upper rounded end of the inside former 13 is a little higher than the upper round ends of the flanging blocks 97, 99 so that when the heel end portion of an upper is placed on the inside former 13 its margin can readily pass rearwardly around the outside of the flanging blocks.

After the outside formers have pressed the heel end portion of the upper against the inside former 13 the driving shaft 175 is caused to be rotated through a single cycle, by means hereinafter described, and the cross-head 7 is moved down and up again by the eccentrics 173. As the cross-head 7 is moved down by the eccentrics the aforesaid rods 83 engage and compress the springs 89 in the aforesaid sleeve members 85 and press inwardly the lower ends of the block carriers 45, 47 thus applying further pressure upon the sides of the upper, the sleeve members 85 rotating inwardly and downwardly during this movement of the crosshead 7. Also as the cross-head 7 moves down the inside former 13 and the aforesaid cam plate 25 which is secured to the aforesaid slide member 11 which carries the inside former 13 are moved downwardly and the aforesaid rectangular grooves 131 in the cam plate cause the flanging members to swing outwardly away from each other. The downward movement of the inside former 13, relatively to the flanging blocks 97, 99 causes the portion of the flange around the heel end portion of the upper to be turned outwardly and the spreading apart of the flanging blocks 97, 99 causes the side portions of the flange to be turned outwardly. The rear faces of the inside and outside formers lie in the same plane which is parallel to the crosshead guideway 5 and the front faces of the flanging blocks are positioned a slightly less distance behind these rear faces than the thickness of the upper, and it may be a stiffener in the upper, with the result that when the margin of the upper is bent outwardly the spring 123 which urges the flanging blocks 97, 99 forwardly is compressed slightly and the flange is bent outwardly parallel to and pressed between these faces.

The machine head 1 has secured to its left hand side a bracket 193 (Figure 1) having a bearing for the left hand end of the driving shaft 175. The bracket 193 has in it a chamber and a worm-wheel 195 rotatably mounted on the driving shaft 175 and is housed in the chamber. A rearwardly extending horizontal worm-gear shaft 197 is rotatably mounted in a bearing 199 which projects rearwardly from the bracket 193.

The forward end of the worm-gear shaft 197 has secured on it a worm-gear 201 which meshes with the aforesaid worm-wheel 195 and the rear end of the shaft 197 has secured on it a pulley 203 which is driven by a belt from a line-shaft or may be driven by other means.

The worm-wheel has in its left-hand side a recess 205 which is arranged to be engaged by

the right hand end of a bolt 207 (Figure 6) which is slidingly mounted in a collar 209 which is secured on the driving shaft 175. The bolt 207 is urged towards the worm-wheel by a spring 208 and its left hand end has on it a head 211 which is arranged to engage a wedge face 213 on a block 215. The block 215 is pivoted at 217 to a clutch arm 219 and is normally held towards the path of movement of the head 211 by a compression spring 221 between the arm 219 and block 215. The block 215 has a downwardly extending lug 223 which enters a recess 225 in the arm 219 and is held by the spring 221 against one side of the recess. When the head 211 of the bolt 207 engages the wedge face 213 on the block 215, as the machine is being stopped, it swings the block 215 about its pivot 217 until the block engages the arm 219. As the bolt 207 thereafter travels along the wedge face 213 on the block it is positively withdrawn from the recess 205 in the worm-wheel 195. Just as the bolt 207 is leaving the recess 205 in the worm-wheel 195 the spring 221 overcomes the friction between the bolt and the recess and moves the block 215 away from the arm 219 and causes the bolt 207 to be withdrawn from the recess 205 in the worm-wheel 195. This arrangement ensures that the bolt 207 is fully withdrawn from the recess 205 and prevents undesirable chattering between the bolt 207 and worm-wheel 195 which may occur if the bolt is not fully withdrawn.

The clutch arm 219 is pivoted on a horizontal stud 227 (Figures 1 and 5) secured in the bracket 193, which is lower than and rearward of the driving shaft 175 and the arm 219 projects upwardly from the stud. The upper end of the arm 219 is engaged by a shoulder 229 formed on the lower side of a substantially horizontal latch arm 231.

The latch arm 231 extends over the upper end of the arm 219 and over the collar 209 on the driving shaft 175. The latch arm 231 at its rear end is pivoted, by a horizontal pin 233 to the lower forked end of an upwardly extending arm 235 of a three-armed lever 237 which is secured on a horizontal laterally extending shaft 239 which is rotatably mounted in the bracket 193. The lever 237 has extending forwardly from it an arm 241 which, when depressed by the operator causes, through the shoulder 239 on the latch arm 231, the arm 219 to be swung rearwardly to allow the bolt 207 to be moved by the spring 208 into engagement with the left hand side of the rotating worm wheel 195 and into the recess 205 in the worm wheel when the recess, during the rotation of the worm-wheel, moves into alignment with the bolt. When the bolt 207 has entered the recess 205 in the worm wheel 195 the driving shaft 175 is rotated and during an early part of the rotation of the driving shaft a cam face 243 (Figure 1) on the collar 209 raises the latch arm 231 and releases the shoulder 239 from the upper end of the arm 219. The arm 219 is thus allowed to be moved forwardly by a spring 245, connected to it and to the bracket 193, into engagement with the collar and as the bolt 207 travels round with the collar the wedge face 213 on the block 215 causes the bolt to be withdrawn from the recess in the worm wheel. The driving shaft 175 is thus disconnected from the continually rotating worm-wheel 195 and may be finally stopped, if it has not previously stopped after a single revolution by the engagement of the head 211 with a shoulder 247 on the arm 219. When the arm 241 is released

a tension spring 249 (Figure 1) connected to an arm 251 of the three-armed lever 237 and to the bracket 193 raises the arm 241 and moves the latch arm 231 forwardly so that its shoulder 229

5 will again engage the front face of the upper end of the arm 219. If the arm 241 is released immediately it has been depressed the arm 241 and latch arm 231 will be returned by the spring 249 and the arm 219 will be moved forwardly by its spring 245 into engagement with the collar without the shoulder 229 on the latch arm 231 being disengaged from the arm 219 and the latter will be raised and lowered idly by the cam face on the collar 209.

10 To prevent the driving shaft 175 from being caused to be rotated until the aforesaid shaft 169 at the upper ends of the eccentric links 171 has been moved fully forwardly and the toggle has been straightened the shaft 239 has projecting

20 forwardly and upwardly from it a stop arm 253 (Figure 1) which normally engages a hook 255 on a hooked lever 257 which is pivoted on a horizontal laterally extending pivot 259 secured in the machine head 1 and prevents the arm 241 from being depressed.

25 As the eccentric links 171 are swung forwardly, as hereinbefore described by means of the treadle and just before they reach their fully forward position, one of them engages an adjustable screw

30 261 in the hooked lever 257 and during the last portion of the forward movement of the eccentric links 171 moves the hook 255 on the hooked lever away from the stop arm 253 and thus allows the arm 241 to be depressed by the operator.

35 When the eccentric links 171 swing rearwardly the hooked lever 257 swings rearwardly into a position in which its hook 255 is beneath the stop arm 253 if the arm 241 has been released. If the arm 241 is released after the machine has

40 been operated and the eccentric links 171 have moved rearwardly and have allowed the hooked lever 257 to move rearward the forward end of the stop arm 253 snaps past the hook 255 which then moves beneath the stop arm.

45 The cam shaft 175 has secured on it a cam 263 (shown in dot and dash lines in Figure 2) which during the rotation of the cam shaft 175 engages the arm 265 of a bell-crank lever which is pivoted on a horizontal laterally extending shaft 277 secured in the machine head a little lower than and forwardly of the driving shaft 175. Another arm 279 of the latter bell-crank lever extends forwardly beneath a rearwardly extending lug 281

50 on the aforesaid slide member 11 which carries the inside former 13. The cam 263 is arranged to actuate the bell-crank lever just after the eccentric links 171 commence to rise and causes the forwardly extending arm 279 of the bell-crank lever to engage the rearwardly extending lug 281

55 on the slide member 11 and positively raise the slide member 11 somewhat, and with it the cross-head 7 and thus assist the springs 29 and 91 which normally raise the slide member and cross-head in overcoming the friction caused by the flanging of the upper.

60 When operating the illustrative machine the operator places the heel end portion of a shoe upper, which may have a stiffener secured in it, around the upper end of the inside former 13 with the edge of its margin which is to be turned outwardly against the gauge plates 133, the gauge plates 133 having previously been adjusted forwardly or rearwardly according to the width of flange which it is desired to turn outwardly.

65 The operator then depresses the treadle lever

and causes the outside former to wipe down and clamp the heel-end portion of the upper against the inside former 13. The operator then, while holding the treadle depressed, depresses the arm 241 and causes the driving shaft 175 to make a single revolution, during which the outside formers are pressed more firmly against the upper and the outside formers and inside former are moved down relatively to the flanging members. During the downward movement of the outside and inside formers the flanging members are spread apart and the flange is formed on the upper. The outside and inside formers are then raised by their springs and by the cam 263 and bell-crank lever and if the treadle is released the outside formers are raised to their highest position and are opened.

When the aforesaid shaft 169 has been swung to its forward position it is positioned above the forward end portion of a lever 283 pivoted on a stud 285 which is secured in a bracket 287 secured on the head 1. The rear end portion of the lever 283 is pivotally connected at 289 to the upper end portion of a link 291 the lower end portion of which is pivotally connected at 293 to an arm 295 which is pivoted on the aforesaid shaft 177. As the shaft 169 is moved downwardly by the eccentric links 171 it engages the forward portion of the lever 283 and moves this portion downwardly, thus raising the rear end of the lever and through the link 291 swinging the arm 295 rearwardly. The arm 295 carries a roll 297 which when the arm 295 is swung rearwardly engages the rod 185 and moves it away from the pin 183. This enables the cross head 7 to be fully raised as soon as the driving shaft has completed a revolution even if the treadle lever is held depressed by the operator.

After the eccentrics 173 have moved the cross head 7 down and have compressed the spring 29 which supports the inside former 13 there may be a tendency for the latter spring to suddenly raise the inside former 13 and cross head 7, as the eccentrics are moving in a direction to raise them, by rotating the driving shaft 175 through the toggle links 171 and eccentrics 173 and moving the bolt 207 of the clutch away from the face of the recess which drives it. To prevent this the illustrative machine is provided with a brake device (Figure 10) which comprises an eccentric 299 secured on the driving shaft and a brake member 301 which is arranged to be engaged by the eccentric. The eccentric is arranged to engage the brake member and tend to retard rotation of the driving shaft 175 during that part of the machine cycle when the spring 29 which supports the inside former 13 is expanding and prevents the spring from suddenly raising the inside former and crosshead.

Having thus described my invention, what I claim as new and desire to secure by Letters Patent of the United States is:

1. A shoe upper flanging machine comprising an inner mould, about which an end portion of an upper to be flanged is placed, outer moulds, for clamping the upper against the inner mould, a slide to which the outer moulds are pivotally connected, means for moving the slide, a movable bar to which the outer moulds are also connected and friction means which act, by retarding movement of the bar, to cause the outer moulds to swing towards each other about their pivotal connections to the slide, during movement of the slide, until they engage the upper.

2. A shoe upper flanging machine comprising

an inner mould, about which an end portion of an upper to be flanged is placed, outer moulds, for clamping the upper against the inner mould, flanging members for spreading outwardly the margin of the clamped upper and gauge plates, for positioning the upper relatively to the moulds, which plates are yieldingly held against the flanging members.

3. A shoe upper flanging machine comprising an inner mould, about which a portion of an upper to be flanged is placed, outer moulds, for clamping the upper against the inner mould, flanging members for spreading outwardly the margin of the upper, operator-actuated means for causing the outer moulds to clamp the upper against the inner mould and power operated means for causing the outer moulds further to clamp the upper and for causing the flanging members to spread outwardly the margin of the clamped upper.

4. A shoe upper flanging machine comprising an inner mould, about which an end portion of an upper to be flanged is placed, outer moulds for clamping the upper against the inner mould, flanging members arranged to spread outwardly the margin of the end portion of the clamped upper, a toggle, operator-actuated means for straightening the toggle, connections between the toggle and the outer moulds for causing the outer moulds to clamp the upper against the inner mould during straightening of the toggle and a power operated eccentric for moving bodily the straightened toggle to cause the flanging members to spread outwardly the margin of the clamped upper.

5. A shoe upper flanging machine comprising an inner mould mounted on a slide, outer moulds mounted on a second slide, a pair of flanging members pivoted on the machine frame, a lever pivotally connected at one end to the second slide and at the other end to a link pivoted on the machine frame, a toggle link pivotally connected at one end to the lever and at the other end to one end of a second toggle link, an eccentric to which the other end of the second toggle link is connected, an operator-actuated means for straightening the toggle links and moving the second slide towards the first slide and for causing the outer moulds to close around the inner mould, power operated means for rotating the eccentric and causing through the straightened toggle the inner and outer moulds and their slides to move relatively to the flanging members, and diverging grooves in said first slide, which grooves are engaged by blocks on said flanging members, which blocks cause the flanging members to move apart, to flange the upper, during the movement of said first slide.

6. In a machine for forming flanges on shoe uppers, the combination of an inside former to receive the end portion of an upper with its marginal portion projecting beyond the bottom of the former, an outside former, manually operated means for moving the formers relatively to each other to engage the upper, upper-flanging means, and power-operated means for moving the formers relatively to the flanging means to form a flange on the upper.

7. In a machine for forming flanges on shoe uppers, the combination of an inside former to receive the end portion of an upper with its marginal portion projecting beyond the bottom of the former, an outside former, manually operated means for moving the outside former relatively to the inside former to engage the upper, up-

per-flanging means, and power-operated means for moving the formers relatively to the flanging means to form a flange on the upper.

8. In a machine for forming flanges on shoe uppers, the combination of a movable inside former to receive the end portion of an upper with its marginal portion projecting beyond the bottom of the former; a movable outside former, manually operated means for moving the outside former relatively to the inside former to engage the upper, upper-flanging means held from movement with the formers, and power-operated means for moving the formers relatively to the flanging means to form a flange on the upper.

9. In a machine for forming flanges on shoe uppers, the combination of a movable inside former to receive the end portion of an upper with its marginal portion projecting beyond the bottom of the former; a movable outside former, manually operated means including a toggle for moving the outside former relatively to the inside former to engage the upper, upper-flanging means held from movement with the formers, and power-operated means including an eccentric for moving the formers relatively to the flanging means to form a flange on the upper.

10. In a machine for forming flanges on shoe uppers, the combination of a movable inside former to receive the end portion of an upper with its marginal portion projecting beyond the bottom of the former, a movable outside former, manually operated means including an inverted toggle for moving the outside former relatively to the inside former to engage the upper, upper-flanging means held from movement with the formers, and power-operated means including an eccentric acting through the inverted toggle for moving the formers relatively to the flanging means to form a flange on the upper.

11. In a machine for forming flanges on shoe uppers, the combination of a movable inside former to receive the end portion of an upper with its marginal portion projecting beyond the bottom of the former, a movable outside former, manually operated means including a toggle for moving the outside former relatively to the inside former to engage the upper, upper-flanging means held from movement with the formers, and power-operated means including an eccentric acting through the toggle for moving the formers relatively to the flanging means to form a flange on the upper.

12. In a machine for forming flanges on shoe uppers, the combination of an inside former to receive the end portion of an upper with its marginal portion projecting beyond the bottom of the former, a two-part outside former arranged to approach and close upon the inside former, manually operated means for operating the outside former relatively to the inside former to conform the upper to the inside former, expandible upper-flanging means, and power-operated means for moving the formers relatively to the flanging means and to expand the flanging means to form a flange on the upper.

13. In a machine for forming flanges on shoe uppers, the combination of an inside former to receive the end portion of an upper with its marginal portion projecting beyond the bottom of the former, means yieldingly opposing endwise movement of the inside former, an outside former comprising two parts arranged to move toward and close upon the inside former, means under control of the operator for moving the outside former relatively to the inside former to engage the upper

per and shape it to the inside former, upper-flanging means held from movement endwise of the inside former, and power-operated means for moving the formers relatively to the flanging means to form a flange on the upper while forming pressure is applied to the upper by overcoming the means for yieldingly opposing movement of the inside former.

14. In a machine for forming flanges on shoe uppers, the combination of an inside former to receive the end portion of an upper with its marginal portion projecting beyond the bottom of the former, a spring opposing endwise movement of the inside former, an outside former, manually operated means for moving the formers relatively to each other to engage the upper, upper-flanging means held from movement endwise of the inside former, and power-operated means connected to the outside former for moving the formers in opposition to said spring relatively to the flanging means to shape the upper and to form a flange on the upper.

15. In a machine for forming flanges on shoe uppers, the combination of an inside former to receive the end portion of an upper with its marginal portion projecting beyond the bottom of the former, an outside former adapted to close about the inside former, manually operated means for closing the outside former and moving the formers relatively to each other to cause the upper to be wrapped about the inside former and rubbed lengthwise thereof, upper-flanging means held from movement with the formers, and power-operated means for moving the formers relatively to the flanging means to form a flange on the upper.

16. In a machine for forming flanges on shoe uppers, the combination of a movable inside former to receive the end portion of an upper with its marginal portion projecting beyond the bottom of the former, a movable outside former, manually operated means including a toggle for moving the outside former relatively to the inside former to engage the upper, upper-flanging means held from movement with the formers, power-operated means including an eccentric acting through the toggle for moving the formers relatively to the flanging means to form a flange on the upper; and means to prevent breaking of the toggle while the eccentric is acting.

17. In a machine for forming flanges on shoe uppers, the combination of an inside former to receive the end portion of an upper with its marginal portion projecting beyond the bottom of the former, a two-part outside former arranged to approach and close upon the inside former, means for operating the outside former relatively to the inside former to wipe the upper lengthwise and to conform the upper to the inside former, a two-part upper-flanging means, the parts being pivoted together and presenting a continuous upper-engaging edge, and means for moving the formers relatively to the flanging means and to separate the flanging means about said pivot to form a flange on the end and sides of the upper.

18. In a machine for forming flanges on shoe uppers, the combination of an inside former to receive the end portion of an upper with its marginal portion projecting beyond the bottom of the former, a spring opposing endwise movement of the inside former, an outside former comprising two parts arranged to move toward and close upon the inside former, means under control of the operator for moving the outside former relatively to the inside former to engage the upper

and shape it to the inside former, upper-flanging means held from movement endwise of the inner former, power-operated means for moving the formers relatively to the flanging means to form a flange on the upper while forming pressure is applied to the upper by overcoming said spring, and means for yieldingly holding the flanging means toward the outside former.

19. In a machine for forming flanges on shoe uppers, the combination of an inside former to receive the end portion of an upper with its marginal portion projecting beyond the bottom of the former, a spring opposing endwise movement of the inside former, an outside former, manually operated means for moving the formers relatively to each other to engage the upper, upper-flanging means held from movement endwise of the inside former, power-operated means connected to the outside former for moving the formers, in opposition to said spring, relatively to the flanging means to shape the upper and to form a flange on the upper, and a spring for holding the flanging means toward the outside former to press the formed flange.

20. In a machine for forming flanges on shoe uppers, the combination of an inside former to receive the end portion of an upper with its marginal portion projecting beyond the bottom of the former, a two-part outside former adapted to close about the inside former, the joint between the parts of the outside former being at one side of a vertical plane passing lengthwise centrally through the inside former, means for closing the outside former and moving the formers relatively to each other to cause the upper to be wiped lengthwise against the inside former, upper-flanging means held from movement with the formers, and means for moving the formers relatively to the flanging means to form a flange on the upper.

21. In a machine for forming flanges on shoe uppers, the combination of an inside former to receive the end portion of an upper with its marginal portion projecting beyond the bottom of the former, a two-part outside former, a carrier for each part of the outside former, said carriers being arranged to close about a center lying in a vertical plane passing centrally through the inside former, means for operating the carriers to cause the outside former to wipe the upper lengthwise and conform it to the inside former, a two-part upper-flanging means, and means for moving the formers relatively to the flanging means and to separate the parts of the flanging means to form a flange on the end and sides of the upper.

22. In a machine for flanging shoe uppers, the combination of an inside former to receive the end portion of an upper with its margin projecting beyond the bottom of the former, means opposing endwise movement of the inside former, an outside former comprising two parts arranged to move toward and close upon the inside former, a carrier for each part of the outside former, a slide for moving the carriers, a link connecting each carrier to the slide, friction means connected to the carriers between the links to cause the carriers to close about the links when the slide is moved, upper-flanging means held from movement lengthwise of the inside former, and means for moving the slide to cause the formers to shape the upper and to move relatively to the flanging means to form a flange on the upper.

23. In a machine for forming flanges on shoe uppers, the combination of an inside former to receive the end portion of an upper with its mar-

gin projecting beyond the bottom of the former, a two-part outside former, a slide, a carrier for each part of the outside former, a link connecting each carrier to one part of the outside former, means restraining bodily movement of the carriers, an inclined spring plunger connected to each carrier so that bodily movement of the carrier lengthwise of the inside former will cause the carriers to close toward the inside former, upper-flanging means held from movement with the formers, and means for moving the slide and formers relatively to the flanging means to shape the upper and form a flange on the upper.

24. In a machine for forming flanges on shoe parts, the combination of an inside former to receive the end portion of an upper with its marginal portion projecting beyond the bottom of the former, an outside former, means for moving the formers relatively to each other to engage the upper, an expansible upper-flanging means held from movement with the inside former and having a groove in its periphery, an expansible gage lying parallel to the bottom of the inside former with its edge in said groove, and means connected to the outside former for moving the formers relatively to the flanging means and for expanding said flanging means to form a flange on the upper.

25. In a machine for forming flanges on shoe uppers, the combination of an endwise movable inside former to receive the end portion of an upper with its marginal portion projecting beyond the bottom of the former, said former being arranged to rock laterally, a movable outside former having a plurality of parts adapted to close on the inside former, manually operated means for closing the outside former relatively to the inside former to engage the upper and apply equal pressure to the two sides thereof, upper-flanging means held from movement with the formers, and means for moving the formers relatively to the flanging means to form a flange on the upper.

26. In a machine for forming flanges on shoe uppers, the combination of a movable inside former to receive the end portion of an upper with its margin projecting beyond the bottom of the former, a movable outside former, means for moving the outside former relatively to the inside former to engage the upper, expansible upper-flanging means held from movement with the formers, a gage lying parallel to the bottom of the inside former to limit the projection of the marginal portion of the upper beyond the bottom of the inside former, said gage being in two pivoted parts, a spring holding said parts together to embrace the flanging means, a stud perpendicular to the bottom of the inside former and carrying said gage, means for axially moving and holding said stud to locate the gage at pre-determined distances from the bottom of the inside former, and means for moving the formers relatively to the flanging means and to expand the flanging means to form a flange on the upper.

27. In a machine for forming flanges on shoe parts, the combination of an inside former to receive the end portion of an upper with its marginal portion projecting beyond the bottom of the former, an outside former, an expansible upper-flanging means having a groove in its periphery, an expansible gage lying parallel to the bottom of the inside former with its edge in said groove, spring means for holding the edge of the gage in the bottom of the groove, and means connected to the outside former for mov-

ing the formers relatively to the flanging means and for expanding said flanging means to form a flange on the upper.

28. In a machine for forming flanges on shoe uppers, the combination of a movable inside former to receive the end portion of an upper with its margin projecting beyond the bottom of the former, a movable outside former, expandable upper-flanging means held from movement with the formers, a gage lying parallel to the bottom of the inside former to limit the projection of the marginal portion of the upper beyond the bottom of the outside former, said gage being in two pivoted parts, a spring holding said parts together to embrace the flanging means, means for moving said gage perpendicular to its own plane to locate it at predetermined distances from the bottom of the inside former, and means for moving the formers relatively to the flanging means to expand the flanging means to form a flange on the upper.

29. In a machine for forming flanges on shoe uppers, the combination of a movable inside former to receive the end of an upper with its marginal portion projecting beyond the bottom of the former, a movable outside former, manually operated means including a toggle for moving the outside former relatively to the inside former to engage the upper, upper-flanging means held from movement with the formers, power-operated means including an eccentric for moving the formers relatively to the flanging means to form a flange on the upper, and means for preventing operation of the eccentric until the toggle has been operated.

30. In a machine for forming flanges on shoe uppers, the combination of a movable inside former to receive the end of an upper with its marginal portion projecting beyond the bottom of the former, a movable outside former, a power-driven shaft, a clutch to connect the shaft to the machine, a manually operated lever for setting the clutch, a latch normally preventing operation of said lever, a toggle for moving the outside former relatively to the inside former to engage the upper, means operated by the toggle for releasing the latch, upper-flanging means held from movement with the formers, and an eccentric acting through the toggle for moving the formers relatively to the flanging means to form a flange on the upper.

31. In a machine for forming flanges on shoe uppers, the combination of an inside former to

receive the end portion of an upper with its marginal portion projecting beyond the bottom of the former, a spring opposing endwise movement of the inside former, an outside former, manually operated means for moving the formers relatively to each other to engage the upper, upper-flanging means held from movement endwise of the inside former, power-operated means connected to the outside former for moving the formers in opposition to said spring, and means for positively restoring the inside former to its initial position.

32. In a machine for forming flanges on shoe uppers, the combination of an inside former to receive the end portion of an upper with its marginal portion projecting beyond the bottom of the former, a spring opposing endwise movement of the inside former, an outside former, manually operated means for moving the formers relatively to each other to engage the upper, upper-flanging means held from movement endwise of the inside former, power-operated means connected to the outside former for moving the formers in opposition to said spring, a lever engaging the inside former, and a cam acting on said lever for positively restoring the inside former to its initial position.

33. In a machine for forming shoe uppers, the combination of an inside former to receive the end portion of an upper, a spring opposing endwise movement of the former, a slide movable lengthwise of the former, an outside former carried by the slide, springs opposing movement of the slide toward the inside former, power means for moving the formers in opposition to said springs, and means for exerting a braking action on said power means during reaction of the springs.

34. In a machine for forming flanges on shoe uppers, the combination of an inside former to receive the end portion of an upper with its margin projecting beyond the bottom of the former, a spring opposing endwise movement of the former, a slide movable lengthwise of the former, an outside former carried by the slide, springs opposing movement of the slide toward the inside former, an upper-flanging device held from movement with the formers, power means for moving the formers in opposition to said springs relatively to said flanging device to form the flange, a brake shoe, and an eccentric acting on the brake shoe during the reaction of said springs.

WILFRID THOMAS MINETT.
